UNITED STATES PATENT OFFICE

163,166

PORTABLE TRAFFIC SIGNAL

Kenneth Collins, Rochester, Mich.

Application May 20, 1950, Serial No. 10,058

Term of patent 3½ years

(Cl. D72—1)

To all whom it may concern:

Be it known that I, Kenneth Collins, a citizen of United States of America, residing at the city of Rochester, in the county of Oakland and State of Michigan, have invented a new, original, and ornamental Design for Portable Traffic Signal, of which the following is a specification, reference being had to the accompanying drawing, forming part thereof.

In the drawing

Fig. 1 is a front elevational view of a portable traffic signal showing my new design;
Figure 2 is a side elevation of the same;
Figure 3 is a rear elevation of the same;
Figure 4 is a top plan view, and
Figure 5 is a bottom plan view.

I claim:

The ornamental design for a portable traffic signal, as shown.

KENNETH COLLINS.
